UNITED STATES PATENT OFFICE.

HENRY BLAIR, OF SAN ARDO, CALIFORNIA, ASSIGNOR OF ONE-HALF TO HENRY M. MADSON, OF SAN LUCAS, CALIFORNIA.

RAILROAD SPIKE.

1,426,453.

Specification of Letters Patent. Patented Aug. 22, 1922.

Application filed December 3, 1921. Serial No. 519,589.

To all whom it may concern:

Be it known that I, HENRY BLAIR, a citizen of the United States, residing in San Ardo, Monterey County, and State of California, have invented a new and useful Improvement in a Railroad Spike, of which the following is a specification.

My invention relates to railroad spikes wherein an anchoring means is arranged to engage the spike to prevent displacement thereof when driven into a tie to secure a rail thereon.

The primary object of my invention is to provide an improved railroad spike.

Another object of the invention is to provide improved anchoring means adapted to prevent the loosening or withdrawal of the spike while in service.

A further object is to provide an anchored spike that may be readily withdrawn for replacement of ties or for other purposes when desired.

A still further object is to provide means for facilitating the application of an anchoring means to secure a rail engaging spike in engagement with a rail.

I accomplish these and other objects by means of the device disclosed in the drawings forming a part of the present specification wherein like characters of reference are used to designate similar parts throughout said specification and drawings, and in which:

Fig. 1 is a perspective view disclosing the application of my improved spike.

Fig. 2 is a transverse section of a rail secured upon a tie by my improved spike.

Fig. 3 is a side elevation of the device as shown in Fig. 2.

Referring to the drawings the numeral 1 is used to designate the shank portion of a railroad spike provided with a head 2 having a lip 3 formed upon the forward side thereof and adapted to engage the flange 4 of a rail 6 when the shank 1 is driven into a tie 7 as shown in the drawings.

An extension 8 is formed upon the head 2 and arranged to extend laterally therefrom to a point beyond the edge of the tie 7, said extension being preferably slightly upwardly bent at its free end as shown in dotted lines in Fig. 3. The top of the head is substantially flat to permit driving of the spike in the usual manner.

A plate 9 having an aperture 11 at one

end thereof is arranged to be placed in engagement with the overhanging end of the extension 8 and to be moved into a position adjacent the side of the tie 7. A plurality of longitudinally spaced apertures 12 are formed at the other end of the plate 9 whereby an anchoring spike 13 inserted through any one of said apertures 12 may be driven into the tie 7 at substantially right angles to the spike shank 1. The spike 13 is preferably pointed slightly downward when driven thereby drawing the extension 8 from its offset position into contact with the top of the tie 7 as shown in Fig. 3 of the drawings, thereby firmly binding the rail engaging spike in position and effectually preventing any loosening of the spike due to stresses applied through the rails.

The extension 8 and the apertures 11 and 12 are so positioned with respect to the shank 1 that when the spike 13 is driven the shank thereof will pass immediately back of the shank 1 thereby insuring against a rearward movement of the spike such as might permit spreading of the rails. It is desirable to drive the spike 13 at a point well down upon the tie to provide a substantial thickness of wood thereabove. However, when the ties are closely placed, the driving of the spike 13 may be facilitated by driving the same through an aperture 12 nearer the top of the tie, the head of the spike being thus brought into a position more conveniently struck by a hammer.

The extension 8 and the aperture 11 are preferably made of rectangular shape thereby preventing any relative turning movement, and the spike 13 and apertures 12 being also preferably made of square or rectangular shape for the same reason thereby preventing any pivotal movement of the plate 9 about either the extension or the spike.

The device disclosed in the drawings is the preferred embodiment of my invention, however I do not desire to limit myself to this precise construction but reserve all such modifications as may fall within the scope of the appended claims.

Having thus described my invention what I claim as new and desire to secure by Letters Patent is:

1. A railroad spike arranged to be driven into a tie and having a lip arranged to engage the flange of a rail; a laterally disposed extension from the lip arranged to

extend over the edge of the tie; and means engaging said extension for anchoring said spike to the tie.

2. A railroad spike arranged to be driven 5 into a tie and having a head provided with a lip arranged to engage the flange of a rail and a lateral extension arranged to extend over the edge of the tie; an apertured plate adapted to engage the end of the lateral extension; and means for securing said plate 10 upon the side of the tie to anchor the spike to the tie.

3. A railroad spike arranged to be driven into a tie and having a head provided with 15 a lip adapted to engage the flange of a rail to secure said rail to the tie, and a lateral extension arranged to extend over the edge of the tie; an apertured plate adapted to engage the end of the extension; and a spike 20 adapted to be inserted through an aperture in the plate and driven into the tie to anchor the rail engaging spike to the tie.

4. A railroad spike arranged to be driven into a tie and provided with a head having 25 a forwardly extending lip adapted to engage the flange of a rail to secure said rail to the tie, and a laterally disposed extension arranged to extend over the edge of the tie; a plate having an aperture at one end thereof 30 adapted to engage the end of the lateral extension; and a spike adapted to be driven into the tie at right angles to the rail engaging spike through an aperture at the other end of the plate to anchor said rail 35 engaging spike to the tie.

5. A railroad spike arranged to be driven into a tie and provided with a head having

a forwardly extending lip adapted to engage the flange of a rail to secure said rail to the tie, and a laterally disposed extension 40 slightly upwardly bent at its outer end and arranged to extend over the edge of the tie when the spike is driven to bring the lip into engagement with the rail flange; a plate having an aperture at one end thereof 45 adapted to engage the end of the extension and having a plurality of apertures at the other end; and a spike adapted to be driven into the tie at right angles to the rail engaging spike through one of said plurality 50 of apertures to hold said plate against the side of the tie and to draw the extension against the tie to anchor said rail engaging spike to the tie.

6. A railroad spike comprising a pointed 55 shank adapted to be driven to a tie, and a head having a forwardly extending lip adapted to engage the flange of a rail; an extension formed upon the head and arranged to extend over the edge of the tie 60 and to rest upon the top thereof when the spike is driven to move the lip into engagement with the rail flange; a plate having an aperture at one end adapted to engage the end of the extension and also having a plurality 65 of longitudinally spaced apertures at the other end adapted to receive a spike driven into the tie at right angles to the rail engaging spike and in engagement with the back of the shank thereof to prevent dis- 70 placement of said rail engaging spike.

In witness whereof I hereunto set my signature.

HENRY BLAIR.
